UNITED STATES PATENT OFFICE.

JOHN E. MUHLFELD, OF BALTIMORE, MARYLAND.

RAILROAD TIE-PLATE.

No. 909,443.

Specification of Letters Patent: Patented Jan. 12, 1909.

Application filed June 21, 1907. Serial No. 380,033.

To all whom it may concern:

Be it known that I, JOHN E. MUHLFELD, a citizen of the United States, residing in Baltimore, in the State of Maryland, have invented a new and useful Improvement in Railroad Tie-Plates, of which the following is a specification.

My invention relates to improvements in track rail tie-plates for railroads.

In the practical use of track rail tie-plates of the constructions heretofore generally employed, much trouble and difficulty are experienced from the fact that the side thrust of the train on the rails exerts a cutting or shearing strain upon the spike which passes through the comparatively thin tie-plate and which is thus shearingly embraced between the metal of the tie-plate at the back of the spike and the comparatively narrow edge of the rail flange on the opposite side or throat of the spike, so that in a short time the side thrust of the train on the rails will soon so shear, cut, bend, wear, break or otherwise distort the spikes as to cause them to loosely or imperfectly hold the rails in place on the ties and to proper gage, thus necessitating much labor and expense for track maintenance.

The object of my invention is to provide a track rail tie-plate of a strong, simple, efficient and durable construction, which may be cheaply manufactured, and by means of which the difficulties heretofore experienced may be practically overcome.

My invention consists in the means I employ, as herein shown and described, for practically accomplishing this object or result. That is to say, it consists in providing the tie-plate adjacent to the spike opening thereby with an integral supplemental support or reinforcement for the back of the spike, preferably on the upper face of the tie-plate and thus affording a direct support for the back of the spike directly opposite or on a line with the edge of the rail flange so that the side thrust of the rail will exert, in connection with the tie-plate, no shearing, bending or breaking action on the spike, and so that the bearing of the tie-plate against the back of the spike will be so increased or enlarged as to effectually remedy or prevent troublesome wear of the rail flanges and tie-plates on the spikes.

My invention further consists in the novel construction of parts and devices and in the

novel combinations of parts and devices herein shown and described.

In the accompanying drawing forming a part of this specification, Figure 1 is a vertical cross section through a track rail, tie and tie-plate embodying my invention. Fig. 2 is a perspective view of my improved construction of tie-plate. Figs. 3 and 4 are vertical sections partly in elevation showing a punch and die suitable for use in forming my improved tie-plate. Fig. 5 is a vertical cross-section showing my tie-plate when used with a rail brace. Fig. 6 shows a modification.

In the drawing, A represents the rail of a railway track, B my improved construction of tie-plate, C the tie and D the spikes.

The tie-plate B is preferably furnished with the customary longitudinal ribs or flanges b on its under face, and with openings b¹ through which the spikes D are inserted.

In order to prevent the edge a of the rail flange A¹ from exerting, in connection with the tie-plate B, a shearing or bending action upon the spikes D under side thrust of the train on the rails, and to provide a direct support for the back of the spike against such side thrust directly opposite and in line with the edge of the rail flange so as to cause the tie-plate and spikes to solidly hold and anchor the rails in proper gage and securely to the ties, I provide the tie-plate B adjacent to the spike opening b¹ therein with an integral supplemental support or reinforcement b² for the spike.

The supplemental support or reinforcement b² is preferably on the upper face of the tie-plate and projects upwardly, and it is also preferably furnished with integral side walls b³ engaging the side faces of the spike.

In the form of my invention as illustrated in the drawing, the tie-plate B is represented as being made from a rolled or channel form of plate. My improved tie-plate may, if desired, however, be made of cast metal. When made of rolled, forged or pressed metal, the supplemental supports or reinforcements b² for the spike are preferably produced integrally with the tie-plate by the same operation which punches or forms the spike openings b¹ in the tie-plate, this being done by simply employing a punch F and die F¹ of suitable form for producing the spike support or reinforcement b² of the desired shape, as illustrated, for example, in Figs. 3 and 4 of the drawing.

- The supplemental support or reinforcement on the tie-plate for the spike, as illustrated in the drawing, preferably surrounds three sides of the spike opening in the tie-plate, although, if desired, it may be made to surround a greater or less number of sides. As in my improved construction of tie-plate, the back d of the spike D has a direct abutment or support against the reinforcement 5 b^2 , and the side thrust pressure of the rail flange edge, a , against the throat or front face d^1 of the spike can exert no bending, breaking or shearing strain against the spike or any strain tending to lift the spike from the tie. And as the bearing wall b^4 of the tie-plate against the back of the spike is doubled or greatly increased, I find in practice that the tie-plate exerts no injurious wearing action upon the spike. I am thus 10 enabled, by means of my improved construction of tie-plate to provide the track rail spike with an efficient support at the throat or under the head thereof and at the back of the same to enable it to effectually resist the pressure of the rail flange which tends to 15 bend, wear, shear, cut or break the spike. I am thus enabled to effectually overcome danger of spreading of the rails or tie-plates. As in my invention, the back of the spike is 20 provided with a support directly in line with the edge of the rail flange, the side pressure of the rail flange on the spikes does not tend to bend the spikes and thus lift the head of the spike from the rail flange and loosen the 25 rails on the ties.
- The tie-plate B at the outside end thereof, or the end thereof which receives the greatest side thrust thereon from the rail flange, is made or provided with two spike openings 30 b^1 , each furnished with a supplemental support b^2 for the back of the spike. At the opposite end of the tie-plate B only one spike opening b^1 is ordinarily used. This spike opening b^1 , however, is provided with a similar upwardly projecting supplemental support b^2 to engage the back of the spike so that 35 the spike at this end of the tie-plate will cooperate with the two at the other end in resisting the side thrust of the rail flange and consequent spreading of the rails, through 40 the coöperative action of the tie-plate B and its engagement against the single spike D at this end of the tie-plate, the supplemental support b^2 projecting above the tie-plate 45 affording an extended bearing of the tie-plate against the spike and preventing the 50 tie-plate from wearing, cutting or distorting the spike or otherwise loosening or distorting the effective or snug engagement of the parts necessary for their effective coöperation.
- The side walls b^3 b^4 of the upwardly projecting spike support b^2 fitting under the head d^2 of the spike serve as a collar to support the spike and in effect to shorten the neck 55 or throat portion of the spike which projects above the upper face of the main web of the tie-plate B and thus to prevent side thrust of the rail flange against the spike from tending to cant the spike and thus loosen the anchor 60 age of the rail on the tie.
- The ends or shoulders b^5 of the side walls b^4 may also engage the edge of the rail flange and thus aid in preventing spreading of the 65 rails.
- When my tie-plate is used with a rail brace, as shown in Fig. 5, the integral spike support or reinforcement projects on the lower side of the tie-plate and the spike extends through a suitable opening in the 70 flange g of the rail brace G .
- Where the tie-plate is furnished with an intermediate rib or flange on its under side in line with the spike opening, as shown in Fig. 6, such rib or flange will form an extended support or reinforcement for the 75 spike on the under side of the tie-plate.
- I claim:
1. A track rail tie-plate B having a spike opening b^1 and an integral upwardly projecting support b^2 for the back of the spike, said support b^2 having side walls b^3 , said projecting support being integral with the tie-plate and formed by the metal displaced in producing the opening in the tie-plate for 80 the spike, substantially as specified.
  2. A railroad tie-plate having a projection on one face thereof adjacent to the spike opening therein and affording a supplemental bearing surface and support for the back 85 of the spike against side thrust of the rail flange, said projection having a back wall engaging the back of the spike and side walls fitting under the head of the spike, said projecting support being integral with the tie-plate and formed by the metal displaced in 90 producing the opening in the tie-plate for the spike, substantially as specified.

JOHN E. MUHLFELD.
